UNITED STATES PATENT OFFICE

2,172,993

TURBINE ENGINE

George D. Sturtevant, Cleveland, Ohio

Application July 14, 1938, Serial No. 219,170

3 Claims. (Cl. 60—42)

This invention relates to an improvement in gas turbines of the type used for propelling heavy transitory bodies, as in the case of a locomotive, and especially to an improvement which permits the expansion of gas substantially at explosion temperatures, and it further relates to a novel method of expanding combusted gas for producing mechanical energy at an increased overall operating efficiency of the turbine.

Heretofore, gas turbines of this type have been operated by heavily jacketing the parts subjected to the high heats if the gas is expanded at the explosion temperatures, or, in some instances, water has been directly introduced into the gas at the nozzles for cooling the gas below the critical temperature of the metal in the blades, or a mixture of gas and steam has been formed before introducing the gas into the turbine header and then expanded through the turbine. The disadvantage of preparing a mixture of gas and steam is the decrease in operating efficiency of the turbine, and in cases where the water is admitted directly to the nozzles, the impinging of the water or saturated steam causes considerable damage to the surface of the blades. A further disadvantage in reducing the temperature of the gas by use of water is that condensation of steam occurs during expansion of the gas, producing vacuums and consequently lowering pressures of the expanding gas, resulting in a further lowering of the overall efficiency of the turbine.

It is a principal object of this invention to provide an improvement in a gas turbine whereby gas may be admitted to the expanding nozzles at the temperatures and pressures of the explosion of gas at constant pressure.

It is a further object of this invention to provide an apparatus for forming steam within the header so that the mixture can be expanded through a selected expanding nozzle, thereby decreasing materially the damage ordinarily occurring to the blades by the introduction of water directly to a selected nozzle, as heretofore described.

It is a further object of this invention to provide an apparatus within the header which superheats the steam formed from the water introduced into the header prior to its introduction into the nozzle.

It is a more specific object of this invention to provide a header construction and means in connection therewith for introducing gas into the nozzles of a high pressure stage of a turbine, whereby gas at relatively high temperatures may be introduced directly to an expanding nozzle or

nozzles and the expanding blades of the apparatus are cooled by a mixture of gas and steam formed within the passage of the header before being introduced into a selected nozzle last receiving expanding gas from the passage within the header.

Further objects of this invention will become apparent from the specification and drawings, in which:

Fig. 1 is a sectional view of an embodiment of the invention;

Fig. 2 is an end view in elevation of the embodiment illustrated in Fig. 1;

Fig. 3 is a diagrammatic illustration showing a system of various power producing elements for supplying gas to the turbine; and

Fig. 4 is a sectional view of the header taken along the line 4—4 of Fig. 1.

In a power producing system which includes a gas turbine, an arrangement as illustrated in Fig. 3 may be used. Generally, this system comprises a gas engine 20 to which is directly connected an air compressor 23 which is used for delivering air at substantially constant pressures to a carburetor 25. The carburetor 25 supplies fuel to the gas producing unit 24, and this unit in turn may be driven as by the gas engine 20 so that the combusted gases delivered from the unit are at higher temperatures and pressures. These gases are discharged from the unit and delivered to a drum 26 which stores the gas and also effectively stabilizes the pressures and temperatures of the gases entering therein which are passed into the turbine 27 for expansion.

The gas turbine used is of the impulse type and comprises a housing 1 which is supported on a frame and base 3. A rotor shaft 2 extends through the housing and is supported by the bearings 4 and 5 which are supported by the frame 3. Onto the rotor 2 is mounted the blade carrying members 6 which are so spaced along the length of the rotor as to define the expanding stages in the housing. Just ahead of each of the blade carrying members 6 is a diaphragm 7 which is mounted into the housing and carries nozzles 8 therein which are spaced from the axis of the rotor a sufficient distance so as to cause the gases expanding therethrough to impinge the blades 9 mounted on the members 6. Ordinarily, as followed in present-day turbine design and manufacture, the nozzles used in each diaphragm are three in number and are spaced substantially 120° apart for providing the proper balancing and support of the rotor.

The combusted gases enter through the inlet 55

- 12 of a header 11 which is mounted onto the high pressure side of the housing 1. The header 11 has a passage 13 therein which in turn has outlet openings 14, 14a and 14b leading therefrom. 5 These openings are spaced in the passage 13 so as to discharge the gases passing through the passage directly into the expanding nozzles located in the diaphragm of the high pressure stage. It is preferred that the opening 12 of the header 10 be located adjacent an opening 14 in the passage so that gas entering the opening 12 of the header can immediately pass through the opening and into a nozzle.

In order that all the gases entering the passage 13 may travel in one direction, there is provided a partition 17 which closes off the travel of gases in the one direction and causes all gases entering the inlet 12 to pass into or by the opening 14 which is located adjacent the inlet opening and thence into an expanding nozzle connected thereto. This arrangement is advantageous in that it allows a portion of the undiluted gases passing through the inlet chamber to be immediately expanded through the turbine, 25 thereby developing the maximum of energy by expansion of the hot gases. The portion of gases which passes by the opening 14 located adjacent the inlet opening 12 travels through the passage 13 to the next opening 14a, a part of which passes 30 therethrough and the remainder of which passes to the last outlet opening 14b.

A second partition 18, completely closing off the passage 13, is located in the passage 13 beyond the opening 14b in the same general direction of travel of the gases and a predetermined distance therefrom so that water which may be admitted through a pipe 30 connected to the passage 13 is allowed to be transformed into steam before passing into the opening 14b. By 35 reason of the velocity of the gases in the passage 13, the effect of the dead end passage formed by the partition 17 in reducing the velocity of gas, as well as other factors, such as frictional resistance and steam formation, all aid in producing such a pressure condition around the vicinity of opening 14b which in turn causes the gas and steam mixture formed in the passage space between the opening 14b and the partition 18 to pass through the opening 14b and 40 nozzle connected thereto and thence into the subsequent expanding stages of the turbine. It is desired that a mixture of steam and gas be admitted through only part of the nozzles since 45 the effect of the mixture is to decrease the operating efficiency of the turbine. As is the case generally in gas turbines, the greater portion of power developed by the gases is in the expansion through the first few stages of the turbine, and it is therefore advantageous and desirable for 50 hot gases uncontaminated with steam to expand through these stages at substantially the temperatures and pressures of explosion, at constant pressure or at which the gas passes into the header 11.

55 Upon starting the turbine, the passage 13 may fill completely with hot gases before any substantial amount of gases passes through the openings in the passage 13 leading to the nozzles, but due to the general motion of the gases from 60 the inlet duct 12 toward the turbine nozzles, which prevents a retrograde flow of the gases, the steam produced will remain in the passage space between the opening 14b and the partition 18, or at least be inhibited from passing in a reverse 65 direction to the openings 14 and 14a.

By admitting superheated steam into less than all of the nozzles, the effect is to cool the blades as they come into contact with the mixture, this being due, of course, to the lower temperature of the mixture as compared with the temperature of the hot gas. Furthermore, by passing the undiluted gas through some of the expanding nozzles in the first or high pressure stage, greater kinetic energy is produced in these nozzles and consequently greater transfer of power to the 10 blades. Cooling of the blades occurs as they come into contact with the steam and gas mixture being discharged from other nozzles in the same stage. By superheating the steam before admitting it into the expanding stages of the 15 turbine, this eliminates or decreases materially the destruction caused to the blades by discharging a mixture of gas and partially vaporized water or saturated steam which may occur by admitting water directly into the nozzle. By 20 this invention, a mixture of gas and steam may be expanded through selected nozzles for the purpose of cooling, and relatively undiluted hot dry gas may be expanded through the remaining nozzles in the stage and the header is so arranged 25 as to discharge hot dry gas into expanding nozzles with the least possible heat loss.

By this arrangement of directing the flow of gas through the passage 11 and into the expanding nozzles, and by the admission of water in a 30 manner so that it is completely transformed into superheated steam, the efficiency of the turbine is materially increased and the rotor blades are maintained at a temperature below the critical point of the material of which such blades are 35 made. A series of redirecting blades, as illustrated at 35, may be used and mounted directly onto the diaphragm 7 in the first or high pressure stage in order to increase the production of power in this stage by taking advantage of the undiluted condition of hot gas. These stationary 40 directing blades may be cooled by a water jacket within the housing, as illustrated at 36.

It is a matter of common knowledge that the fluid friction of superheated steam as it passes 45 over the blade surfaces is materially less than that of saturated steam and consequently it is advantageous that the steam existing in the gas in the expanding stages of the turbine be superheated. Likewise, if the steam is heated only to 50 a saturation point, the expansion of the gas and of the steam causes a condensation of the steam, resulting in the formation of vacuums within the stages and material decreases in gas pressure. Also, because of the high velocities of the mixtures, water vapor causes considerable damage to 55 the blade surfaces. By the admission of gas directly from the drum 26, or as illustrated in Fig. 1, from the header 11, to the several stages in the turbine, the steam is maintained substantially in 60 a superheated condition. By so maintaining the steam in a condition of superheat, an increased expansion occurs in the gases on passing through an expanding nozzle, correspondingly increasing the power transfer. To accomplish this, a heavy 65 pipe conductor 37 supported along a side of the turbine housing and base from which the smaller conductors 38 are connected thereto is illustrated as being connected to the header 11. Each of the conductors 38 passes through the turbine 70 housing 1 and is positioned in each of the stages just ahead of the diaphragm 7 in each stage so that the gas passing from the succeeding stage comes into contact with the gas being discharged from the conductor 38, causing a heating of the 75

mixture and especially the steam component for producing greater expansion of the gases as they pass through the nozzles in the succeeding stages. As illustrated in Figs. 1 and 2, the conductor 38 has a valve 40 therein for controlling the supply of gases to its respective stage. This introduction of hot gas into the expanding stages beyond the high pressure or initial stage equalizes the power production along the rotor so that increased power can be produced in these latter stages, whereupon more power is produced by the turbine and the power generation is distributed in a more equal fashion all along the rotor length.

Having thus described my invention, I claim:

- 5 1. A gas turbine having a housing, a rotor supported by the housing, rotatable blades supported by said rotor, nozzle means mounted onto an end of said housing and in relation to the rotatable blades and comprising a circular header mounted onto the nozzle end of said housing and having a central annular passage therethrough, said header having an inlet opening for connecting the passage of the header to a source of expansible gas, a plurality of outlet openings 20 in the pasage and arranged for fluid connection with the nozzle means, a partition in the passage for causing all of the gas entering the header to travel in one general direction of movement, a water inlet means for introducing water into the 25 passage and positioned beyond the last outlet opening as defined by the one general direction of movement, and a second partition positioned beyond the water inlet means as defined by the general direction of travel of the gas and positioned in a predetermined manner in relation to the last outlet opening, whereby substantially all of the gas and steam mixture formed by introducing water into the passage passes through the last outlet opening for effectively cooling the 30 rotatable blades of the turbine.
- 15 2. A gas turbine header for a turbine engine having a housing, a rotor mounted within the housing, a plurality of nozzles leading to an expanding stage of the turbine, blades mounted

onto the rotor and positioned relative to said nozzles for receiving expansible heated fluid and comprising a header body having a central annular passageway with outlets connected to said nozzles, an inlet opening for receiving heated expansible fluid, a partition adjacent said inlet opening and in said passage for causing all fluid entering the passage to travel in one general direction of movement, and means for introducing an evaporable cooling medium into the passage 10 and positioned beyond the last outlet opening in the passage defined by the one general direction of movement of the fluid, whereby the cooling medium, upon introduction into the passage, is evaporated and a substantial portion of the 15 evaporated medium passes through said last outlet in the passage.

3. A gas turbine header for a turbine engine having a housing, a rotor mounted within the housing, a plurality of nozzles leading to an expanding stage of the turbine, blades mounted onto the rotor and positioned relative to said nozzles for receiving expansible heated fluid and comprising a header body having a central annular passageway with outlets connected to said nozzles, an inlet opening for receiving heated expansible fluid, a partition adjacent said inlet opening and in said passage for causing all fluid entering the passage to travel in one general direction of movement, a second partition in said 20 passage for interrupting the flow of fluid in the one general direction of movement in said passage and positioned in close proximity to the last outlet opening in the passage defined by the one general direction of movement of the fluid, 25 and means for introducing an evaporable cooling medium into the passage and positioned between the second partition and said last outlet opening, whereby the cooling medium is evaporated upon introduction into the passage and a substantial portion of the evaporated medium passes through said last outlet opening in the passage to the expanding stage of the turbine.

GEORGE D. STURTEVANT.
